(57) **CLAIM**

The ornamental design for a cutting tool handle, as shown and described.

DESCRIPTION

FIG. 1 is a perspective view of a novel design for a handle for receiving a tool such as a knife;

FIG. 2 is a top plan view of the handle of FIG. 1;

FIG. 3 is a side elevation of the handle of FIG. 1;

FIG. 4 is a left end view as seen in FIG. 1, including a design feature inscribed thereon; and,

FIG. 5 is a right end view as seen in FIG. 1.

The broken lines shown in the drawings are for illustrative purposes only and form no part of the claimed design.
